BAGGAGE FASTENER

Filed March 5, 1929

UNITED STATES PATENT OFFICE

ARTHUR H. ELLIS, OF ROCHESTER, MINNESOTA

BAGGAGE FASTENER

Application filed March 5, 1929. Serial No. 344,518.

The present invention relates to improvements in baggage fasteners, and has reference more particularly to a means for positively securing baggage such as tents, bedding, etc., 5 that is placed upon the top of a car.

One of the important objects of the present invention is to provide a baggage fastener that includes strap members for disposition across the baggage or luggage placed on the 10 top of the car, means being associated with the ends of the respective straps for attaching the same to the rain gutters or troughs arranged at the opposite sides of the top of the vehicle of the closed type.

15 Another important object of the invention is to provide a baggage fastener of the above mentioned character that can be readily and easily attached to the top of a closed car and adjusted for disposition over the luggage 20 or baggage to secure the same in proper position on the top of the car, and this without causing any injury to the top of the car or to the rain trough or gutters.

25 Another important object of the invention is to provide a baggage fastener of the above mentioned character which is simple in construction, inexpensive, strong and durable and further well adapted to the purpose for which it is designed.

30 Other objects and advantages of the invention will become apparent from the following description when taken in connection with the accompanying drawing.

In the accompanying drawing wherein 35 like reference characters indicate corresponding parts throughout the same:

Figure 1 is a perspective view illustrating the manner in which my improved baggage 40 fastener is secured on the top of an automobile of the closed type for retaining the baggage or luggage that is placed on the top of the automobile.

Figure 2 is an end elevation showing more 45 particularly the clamping means associated with the baggage fastener for attachment to the rain trough or gutter that extends along each side of the body of the vehicle adjacent the top thereof.

50 Figure 3 is a transverse section taken ap-

proximately on the line 3—3 of Figure 2 looking downwardly, and

Figure 4 is a detail perspective view of one of the vertically disposed arms forming a part of the baggage fastener. 55

In the drawing wherein for the purpose of illustration is shown the preferred embodiment of my invention, the numeral 1 designates the top of an automobile of the closed body type and extending along the 60 sides of the body adjacent the top thereof are the usual rain troughs or gutters 2. Frequently tourists or campers will place their baggage or luggage on the top of the car so as to avoid taking up any space within the 65 interior of the car or upon the running boards.

Where the luggage or baggage is thrown on the top of the car, there is always a possibility of the same falling off during the 70 movement of the car, and it is therefore the principal aim of the present invention to provide a fastener for positively securing the baggage or luggage on the top of the car against displacement therefrom. 75

My improved baggage fastener comprises a pair of complementary units for disposition adjacent the respective side edges of the top and as each of these units is of identical construction, the description of one is thought 80 to suffice for the description of both. Each unit is designated by the numeral 3, and the same includes a pair of vertically disposed spaced arms 4—4. Each arm is formed from a flat strip of metal, the upper end of which 85 is bent back upon itself to form a loop 5, while the side edges of the lower end portion of the strips are bent inwardly to form nut engaging flanges 6.

An elongated flat strip 7 extends across the upper end portions of the spaced arms 4 and the end portions of this strip are fixedly secured to the respective arms by any appropriate fastening means such as is shown at 8. 90

Attached to each looped upper end 5 is 95 the rectangular shaped ring or bail 9. Suitable straps 10 are attached at their outer ends to the loops or bails 9 associated with the unit that is secured on one side of the top 1. Similar straps 12 are attached at their outer 100

ends to the loops or bails 9 associated with the unit that is secured on the opposite side of the top 1, and suitable buckles 11 are carried by the free ends of the straps 10 for cooperation with the free ends of the complementary straps 12 to secure the respective straps together in their tightened position over the luggage or baggage A that is placed on the top 1 of the automobile.

10 For the purpose of detachably securing the units 3 to the respective rain troughs or gutters, I provide a pair of clamps 13 for each unit and in Figure 2 there is disclosed more clearly the construction of each of these 75 clamps. Each clamp is formed from a strip of metal that is curved at its respective end portions and the lower end portion of each clamp has arranged on its inner face a felt strip 14 that is adapted to engage against the 80 outer edge portion of the trough or gutter 2 so that said clamps will not deface or otherwise damage the trough or gutter.

The upper portion of each clamp 13 is formed with an opening that registers with 25 a similar opening 15 formed in the lower end portion of each arm 4 and a headed bolt has its shank 16 disposed through the registering openings in the arm 4 and the respective clamp 13. The head 17 of each bolt is of rectangular shape for disposition against the 30 outer face of the lower end portion of each arm and the inwardly directed flanges 6 engage with the respective sides of the head 17 to prevent turning of the bolt. A wing nut 35 18 is threaded on the outer end portion of the shank 16 of each bolt for engagement with the outer face of the clamp 13 and obviously when the parts are arranged as shown in Figure 2, the clamp 13 will fixedly secure the 40 respective unit to the respective troughs or gutters.

When the baggage fastener is in use, there will be no possibility of the baggage or luggage accidentally falling off of the top of the car, and furthermore said fastener can be readily and easily disassembled to facilitate the removal of the same from the vehicle. By disconnecting the free ends of the straps 12 from the buckles 11, the baggage or luggage 50 may be removed without necessitating the entire removal of the baggage fastener from the car.

The simplicity of my device enables the same to be constructed at a very low cost, and 55 furthermore the device can be readily and easily attached or removed.

While I have shown the preferred embodiment of my invention, it is to be understood that minor changes in the size, shape and arrangement of parts may be resorted to without departing from the spirit of the invention, and the scope of the appended claims.

Having thus described the invention, what I claim as new and desire to secure by Letters Patent is:

1. In combination with a vehicle top, and the troughs extending along the side edges thereof, a pair of arms, means for detachably securing said arms at their lower ends to the respective troughs, and a flexible connection between the upper ends of the arms for disposition across baggage placed on top of the vehicle to secure the same thereon, said first mentioned means comprising a clamp for association with the lower end of each 75 arm, the lower end of each arm being disposed within the respective trough, the lower portion of the respective clamp being adapted for engagement with the outer edge of the adjacent trough, and a bolt and nut 80 connection between the upper portion of each clamp and the adjacent portion of the respective arm.

2. In combination with a vehicle top, and the troughs extending along the side edges thereof, a pair of vertically disposed arms for disposition at each side of the top, an elongated bar inner-connecting the arms of each pair, the upper end of each arm being formed with a loop, a flexible connection between the looped upper ends of the opposed arms for disposition across baggage placed on top of the vehicle to secure the same thereon, and means for detachably securing the arms at their lower ends to their respective troughs, comprising a clamp for association with the lower end of each arm, the lower end of each arm being disposed within the respective troughs, the lower portion of the respective clamps being adapted for engagement with the outer edge of the adjacent trough, a bolt and nut connection between the upper portion of each clamp and the adjacent portion of the respective arm, each of said arms being formed with laterally disposed flanges at the side edges of the lower end thereof, to prevent rotation of the respective bolt.

In testimony whereof I affix my signature.
ARTHUR H. ELLIS.
